METHOD OF CHARGING REFRIGERATING SYSTEMS

Graham S. McCloy, Springfield, Mass., assignor to Westinghouse Electric & Manufacturing Company, East Pittsburgh, Pa., a corporation of Pennsylvania

Application May 16, 1940, Serial No. 335,441

8 Claims. (Cl. 62—170)

My invention relates to refrigeration apparatus, and more particularly to a method and apparatus for charging a refrigerating system with refrigerant and lubricant and for removing non-condensable gases from the system.

In charging a closed refrigerating system it is necessary for several reasons to remove substantially all non-condensable gases such as air from the system. The presence of non-condensable gases in the system is objectionable for several reasons as is well known in the art. For example, the presence thereof causes high head pressures in the high pressure side of the system and hence reduces the efficiency of the system.

Heretofore, refrigerating systems generally have been charged with liquid refrigerant by first drying the refrigerating system with warm air or inert gas and then evacuating the system with high vacuum apparatus. The apparatus for performing the evacuation portion of the process is expensive and slow in operation and, in addition, the refrigerant and lubricant with which the system is afterwards charged contains non-condensable gases which are not removed by prior evacuation. Furthermore, such a system is not conducive to mass production methods wherein the refrigerating systems during assembly and charging are preferably disposed on moving conveyors. This invention is an improvement on the systems disclosed and claimed in McCloy Patent No. 2,181,853, Anderson and McCloy Patent No. 2,181,854, and McCloy Patent No. 2,181,855, all assigned to the assignee of the present application.

It is an object of the present invention to provide an improved method for charging a refrigerating system with both a refrigerant and lubricant and for removing non-condensable gases from the system.

It is another object of the invention to charge a refrigerating system with both refrigerant and lubricant by the container methods disclosed in the aforesaid patents wherein both the refrigerant and lubricant for initially charging the system are contained in a container attached to the system during charging.

It is a further object of the invention to charge a refrigerating system with both refrigerant and lubricant by the container methods disclosed in the aforesaid patents and in which the moving parts of the compressor or the motor and compressor are quickly provided with lubricant during charging so that the moving parts of the apparatus are not damaged.

These and other objects are effected by my

invention as will be apparent from the following description and claims taken in connection with the accompanying drawing forming a part of this application, in which the single figure of the drawing is a diagrammatic view of a refrigerating system to which my invention is applied.

Referring specifically to the drawing for a detailed description of the invention, the refrigerating system includes a hermetically-sealed motor-compressor unit 10 including a compressor 11, a motor 12 for driving the compressor and a casing 13 enclosing the motor and compressor. In normal operation a lubricant reservoir 14 is disposed in the hermetically sealed casing 13 for lubricating the moving parts of the compressor unit 10 such as the bearings 15 and 16.

The inlet of the compressor shown at 17 is connected directly to a compressor head 18 so that refrigerant vapor is withdrawn from an evaporator 19 through a conduit 21 and enters the compressor 11 without entering the interior of the sealed casing 13. The compressor 11 discharges high pressure refrigerant gas into the casing 13 so that the interior of the casing 13 contains gas at substantially condenser pressure. The high pressure gas from the casing 13 is conveyed to a condenser 22 through a conduit 23. Refrigerant is condensed in the condenser 22 by the cooling action of air which is forced over the condenser by a motor driven fan 24. The condensed refrigerant is conveyed through a suitable screen 25 to a capillary tube 26 which regulates the flow of condensed refrigerant to the evaporator 19. After refrigerant is vaporized in the evaporator 19 thus absorbing heat, it is returned to the compressor 11 through the conduit 21 and the cycle is then repeated. The system is so designed that, at least under certain conditions, a mixture of liquid and gas is forced through the capillary tube 26, which fact is important in the further operation and description of the invention.

In accordance with the present invention, a charging drum or vessel 27 is provided, which vessel 27 contains substantially the exact charge of refrigerant and lubricant for charging the refrigerating system, both the refrigerant and lubricant charge having been carefully measured by weight. The refrigerant may be, for example, dichlorodifluoromethane, sold under the trade name of Freon-12 and the lubricant is preferably a high-grade mineral lubricant. The drum 27 is connected to the interior of the sealed casing 13 by a conduit 28 having a hand valve 29 therein, which conduit 28 is attached to a

conduit 30 which has been welded to an opening 31 in the casing 13.

After the mechanical structure of the refrigerating system is completed and before it is charged, the system is first dehydrated, which is preferably effected by subjecting the same to a flow of warm dry air or inert gas for a sufficient time to substantially remove all the moisture from the system. After dehydration, the system, still filled with warm air or inert gas, is placed on the conveyor. During this time the system is open to the atmosphere through the opening 31 in the sealed casing. The pressure throughout the system is substantially at atmospheric pressure and the entire system is above room temperature, having been heated by the warm dry air or inert gas used for drying so that very little, if any, air from outside the system will enter it.

The compressor may now be operated for a short period, for example, about 5 minutes to effect partial evacuation of the low pressure side of the system. This operation is also known as auto-evacuation, since it is effected by operation of the refrigerant compressor. The compressor withdraws non-condensable gases present in the low pressure side of the system and discharges such gases to atmosphere through the opening 31. The pressure in the low pressure side of the system is thereby reduced to about 25 inches of vacuum or lower. The auto-evacuation step is, however, optional as the container 27 may be made of sufficient size to contain all the non-condensable gases present in the system without auto-evacuation.

The drum 27 and conduit 28 are then connected to the conduit 30 in the sealed casing 13 with the hand valve 29 closed and preferably with the compressor 11 inactive. After the drum 27 and conduit 28 have been connected, the hand valve 29 is opened and substantially all of the refrigerant and lubricant contained in the vessel 27 flows through conduit 30 and opening 31 into the sealed casing 13, by gravity. It will, therefore, be apparent that lubricant is present in the sealed casing very soon after the valve 29 is opened to provide for lubrication of the bearings 15 and 16. In addition to the gravity flow of refrigerant into the sealed casing 13 the refrigerant pressure in the vessel 27 at room temperature is usually sufficient to assist the gravity flow of refrigerant and lubricant. This is true of refrigerants, such as F-12, which have a pressure above atmospheric at room temperatures. A short period of time is preferably allowed to permit the liquid refrigerant and lubricant to enter the system.

Operation of the compressor is then again initiated and lubrication of the working parts thereof is insured by the presence of the lubricant 14 in the sealed casing 13. The non-condensable gases which are contained in the system at this time are circulated throughout the system with the refrigerant since, as stated heretofore, the system is designed so that the capillary tube 26 will pass a mixture of gas and liquid under these conditions. The compressor, therefore, removes gaseous refrigerant vapor and non-condensable gases from the low pressure side of the system and discharges them into the high pressure side of the system including the interior of the sealed casing 13, the vessel 27 and the condenser 22. Most of the refrigerant is condensed in the condenser so that a mixture of liquid refrigerant and gaseous fluid, both re-

frigerant vapor and non-condensable gases, flows through the capillary tube 26.

A mixture of gaseous refrigerant at high pressure and non-condensable gases also flows through the conduits 30 and 28 and into the vessel 27. Because of the flow of gases into the vessel 27 the pressure therein increases. Since the bomb is intimately connected with the high side, the pressure in it and the high side will rise at substantially the same rate. As the condensing pressure is approached, refrigerant vapor contained in the mixture begins to condense inasmuch as the vessel 27 is exposed to the ambient atmosphere which is usually at the same temperature as the air circulated over the condenser 22 by the fan 24. The liquid refrigerant resulting from such condensation drains by gravity back into the system and tends to reduce the pressure therein sufficiently to effect the above-mentioned flow of fluid mixture from the sealed casing 13 to the vessel 27. The non-condensable gases entering the vessel 27 are not condensed so that they accumulate within the vessel 27. During this time, non-condensable gases contained in the refrigerant and lubricant are also removed and are collected in the vessel 27.

After the refrigerating system has been operated for a sufficient time, for example, an hour, to collect substantially all the non-condensable gases in the vessel 27, the tube 30 is preferably pinched off below the valve 29 and sealed.

From the foregoing, it will be apparent that I have provided an improved method of charging both refrigerant and lubricant into a refrigerating system by the container method described in the aforesaid patents and for providing a method of charging lubricant by the container method in which lubrication of the working parts of the refrigerating apparatus is insured during the step of removing non-condensable gases from the system and transferring them to the container. Furthermore, it is obvious that both refrigerant and lubricant charging may be effected in a refrigerating system by the method described while the refrigerating system is moving on a conveyor.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. The method of charging a refrigerating system including an evaporator, a compressor, a condenser and an expansion device, with refrigerant and lubricant and removing non-condensable gases from said system, which method comprises connecting to the system a container containing refrigerant and lubricant for charging the system, transferring refrigerant and lubricant from the container to the system, transferring non-condensable gases from the system to the container by operating the compressor to effect flow of a mixture of non-condensable gases and refrigerant vapor into the container, condensing refrigerant vapor in the container and returning the refrigerant condensed in the container to the system.

2. The method set forth in claim 1 and further including closing communication between the system and the container and disconnecting the container from the system.

3. The method of charging and removing non-condensable gases from a refrigerating system including an evaporator, a condenser, an expansion device, and a compressor enclosed in a gas-tight casing, which method comprises connecting to said casing a container containing refrigerant and lubricant for charging the system, transferring refrigerant and lubricant from the container to the system, transferring non-condensable gases from the system to the container by operating the compressor to effect flow of a mixture of non-condensable gases and refrigerant vapor into the container, condensing refrigerant vapor in the container and returning the refrigerant condensed in the container to the system.

4. The method of charging and removing non-condensable gases from a refrigerating system including an evaporator, a condenser, an expansion device and a compressor disposed in an enclosed casing in which high pressure refrigerant discharged from the compressor is present, which method comprises connecting to said casing a container containing refrigerant and lubricant for charging the system, transferring refrigerant and lubricant from the container to the system, transferring non-condensable gases from the system to the container by operating the compressor to effect flow of a mixture of non-condensable gases and refrigerant vapor into the container, condensing refrigerant vapor in the container and returning the refrigerant condensed in the container to the system.

5. The method set forth in claim 4 and further including closing communication between the container and the casing and disconnecting the container from the casing.

6. The method of charging and removing non-condensable gases from a refrigerating system including an evaporator, a condenser, an expansion device, and a motor and compressor disposed in an enclosed casing, which method comprises connecting to said casing a container containing refrigerant and lubricant for charging the system, transferring refrigerant and lubricant from

the container to the system, transferring non-condensable gases from the system to the container by operating the compressor to effect flow of a mixture of non-condensable gases and refrigerant vapor into the container, condensing refrigerant vapor in the container and returning the refrigerant condensed in the container to the system.

7. The method of charging and removing non-condensable gases from a refrigerating system including an evaporator, a condenser, an expansion device, and a motor and compressor disposed in an enclosed casing in which high pressure refrigerant is present and which casing connects with said condenser, which method comprises connecting to said casing a container containing refrigerant and lubricant for charging the system, transferring refrigerant and lubricant from the container to the system, transferring non-condensable gases from the system to the container by operating the compressor to effect flow of a mixture of non-condensable gases and refrigerant vapor into the container, condensing refrigerant vapor in the container and returning the refrigerant condensed in the container to the system.

8. The method of charging and removing non-condensable gases from a refrigerating system and including an evaporator, a condenser, an expansion device, and a compressor, which method comprises connecting to the system a container containing substantially the exact initial charge of both refrigerant and lubricant for the system, transferring refrigerant and lubricant from the container to the system, transferring non-condensable gases from the system to the container by operating the compressor to effect flow of a mixture of non-condensable gases and refrigerant vapor into the container, condensing refrigerant vapor in the container and returning the refrigerant condensed in the container to the system.
